UNITED STATES PATENT OFFICE

NICHOLAS C. GUIDEN, OF BRISTOL, CONNECTICUT, ASSIGNOR TO J. H. SESSIONS & SON, OF BRISTOL, CONNECTICUT, A CORPORATION OF CONNECTICUT

HANGER SUPPORT FOR WARDROBE TRUNKS

Application filed April 18, 1929. Serial No. 356,054.

My invention relates to the class of devices employed for supporting clothes hangers more particularly in connection with wardrobe trunks, and an object of my invention, 5 among others, is the production of such a support that, while having means for limiting swinging movement of the swinging member of the structure may at the same time be used on either side of the trunk.

10 One form of a device embodying my invention, and in the construction and use of which, the objects herein set out, as well as others, may be attained, is illustrated in the accompanying drawings in which—

15 Figure 1 is a view in cross section through a trunk near that end which is uppermost when the trunk is placed in position for use as a wardrobe, my improved support being attached thereto and shown in its folded condition, the trunk cover being removed.

Figure 2 is a view similar to Figure 1 but with a portion of the trunk structure broken out, the support being shown in its open or extended position.

20 Figure 3 is a view in section on a plane denoted by the dotted line 3—3 of Figure 1, but showing a clothes hanger in place.

Figure 4 is a view of a fragment of a trunk showing my improved support in side 25 elevation and in extended condition.

Figure 5 is an isometric view, scale enlarged, of my improved support.

Figure 6 is an isometric view of a fragment of a trunk showing my improved device 30 secured in place on one side thereof.

It has been common practice, prior to my invention, to provide hanger supports that are affixed to the inner surfaces of the sides of wardrobe trunks for the purpose of receiving clothes hangers on the upper sides of said supports. Owing to their peculiar construction it has been necessary to provide two supports for a single trunk, one for the right and the other for the left hand side thereof, 45 in order that a stop may properly function to limit the swinging movement of the swinging arm.

My improved hanger support, as in prior 50 structures, comprises two supporting bracket members each with a stationary hanger sup-

port and a swinging hanger support mounted thereon, but I so form one of the bracket members and the swinging support that structures of like construction may be applied to either side of the trunk, and I, therefore, 55 require only a single construction of the support.

Such improved hanger support is illustrated in the accompanying drawings in which the numeral 7 indicates a trunk of ordinary and well-known construction to the inner surfaces of the sides of which my improved support is attached.

This support comprises a bracket member 8 for one end of a stationary support 9, in 65 the structure herein shown, the support 9 constituting an integral part of the bracket 8 (in the form of a strap) and extending at substantially a right angle thereto. This bracket 8 is secured to the back or bottom wall 60 of the trunk, depending upon its position. A swinging support 10 is pivotally attached to the outer end of the support 9, said swinging support having an offset part 11 underlying the stationary member 9 in order that 65 these two supports may be located substantially in the same plane. The shoulder of the offset part is so positioned and the end of the member 9 is so formed that the swinging support 10 may be swung in either direction 70 from its position in line with the member 9.

A particular feature of my invention resides in a universal bracket 12 arranged to be secured to a side wall of a trunk and having a supporting arm 13 extending at an angle to the bracket and a spacing part 14 extending at an angle to the arm 13 substantially 75 parallel with the bracket 12.

An important feature of my invention resides in a supporting lip 15 that is pivotally attached to the stationary support 9 so that the universal bracket, that, in fact, includes the arm 13, spacing part 14 and lip 15, may be variously positioned with respect to the 80 support 9, that is, the bracket 12 may be located to project at either side of said support.

In affixing the supports to the inner walls 85 of a trunk the bracket 12 is located on one side 90

of the support 9 for one side of the trunk and on the opposite side of said support for the opposite side of the trunk, the pivotal attachment of the lip 15 to the support 9 enabling this result to be attained.

The inner end of the swinging support 10 is offset from the offset part 11 and is extended so that it will rest against the spacing part 14 of the bracket when the support 10 is extended, this last mentioned offset portion therefore forming a stop 16 resting against the part 14 in either position of the bracket with respect to the support 9 and thereby, in both cases, fixing the position of 15 the swinging support 10 in line with the stationary support 9. The stop 16 is offset, as above described, in order that it may swing under the supporting lip 15, and as shown in Figure 5 of the drawings.

20. I claim—

1. A hanger support including a supporting member, a swinging support pivotally attached to said member, and a bracket including a base, an angularly disposed arm 25 extending laterally of said base and a back turned lip also extending laterally of said base pivotally attached to said supporting member to locate said bracket on either side of said support.
2. A hanger support including a supporting member, a swinging support pivotally attached to said supporting member, and a bracket including a base, an angularly disposed arm and a back turned lip pivotally 35 attached to said supporting member, the end of said swinging support being extended to engage said bracket as a stop to limit swinging movement of said swinging support.
3. A hanger support including a supporting member, a swinging support pivotally 40 attached to said supporting member, a bracket including a base, a spacing part at the end of an angularly disposed arm and a back turned lip from said spacing part pivotally attached to said support, a pivot for attaching said lip to said supporting member and an offset part at the end of said swinging support and underlying said lip in position to engage said bracket as a stop to limit 45 swinging movement of said swinging member.
4. A hanger support including a supporting member, a swinging support pivotally attached to said member, and a bracket including a base, a lip extending transversely 50 to said base and pivotally attached to said support and a part projecting from said lip for engagement of the end of said swinging member.

60. NICHOLAS C. GUIDEN.
